AIR BOUND SIPHON FLUSH TANK

Filed Jan. 9, 1929

UNITED STATES PATENT OFFICE

HARMON D. MOISE, OF SUMTER, SOUTH CAROLINA, ASSIGNOR TO MICHAEL B. CROSS, OF EUTAWVILLE, SOUTH CAROLINA, AND RAYMON SCHWARTZ, W. YATES YEADON, SOPHIA BRUNSON, AND MARION W. SEABROOK, OF SUMTER, SOUTH CAROLINA

AIR BOUND SIPHON FLUSH TANK

Application filed January 9, 1929. Serial No. 331,218.

This invention relates to air bound siphon flush tanks and especially to the provision of means for insuring the recharging of the air chamber automatically after each flush.

5 Heretofore this has not been satisfactorily accomplished and the air bound siphon flush tank has been consequently restricted in its usefulness and in many instances entirely avoided or where already installed has been 10 abandoned. The sniff hole in the bell has been one means heretofore provided for recharging with air but owing to its liability to become obstructed it has created great distrust of air bound siphons. An air entraining device whereby the incoming water (under pressure) was utilized to entrain and conduct air to the air chamber was subject to the same objection—it would become obstructed.

15 These two methods were both necessarily limited as to their possible maximum bore and hence the obstruction of the bore was all the more likely to occur, quickly. A subsidiary siphon, positioned within the bell extending below it slightly, and discharging 20 into the main discharge pipe was also used for the same purpose heretofore, namely by lowering the liquid contents of the flush tank below the bottom of the bell to thus allow the recharging of the air chamber after each 25 flush. This also would become obstructed and proved objectionable in other respects.

30 By the present invention a force is utilized (which force is generated by the downward pull of the liquid being discharged) to energize a spring or lift a weight or compress a gas or in any other manner to store up energy. This energy pulls the bell downwardly during the latter part of the flush, thus becoming stored up in the actuating device of 35 whatever nature, and when the siphon breaks after discharging the contents of the flush tank this stored energy immediately raises or lifts the bell to a higher level than it occupied when the flush ended and thus the bell 40 being above the level of the liquid in the flush tank the air chamber recharges itself with air.

45 Although in an air bound siphon flush tank the liquid contents are discharged to an extent by the mere force of gravity, yet, after

the liquid content of the flush tank has been lowered to the level of the top of the discharge pipe and continuously thereafter until the siphon breaks, the bell becomes a member of a siphon and the liquid is lifted in the bell up to a sufficient height to be discharged into the discharge pipe by siphonic action within the bell. A downward pull is generated (by this siphonic action) upon the bell and it is this force which is stored up in a spring or its equivalent, which is utilized to pull the bell downwardly a limited predetermined distance to store up force enough to again raise the bell to its normal elevation after the siphon breaks.

55 In the accompanying drawings springs only are shown as the energy storing means, but any other suitable agent may be employed to receive the energy and upon the breaking of the siphon to lift the bell up again to the level it occupied before it was pulled down from its normal position. In case of automatic operation, the bell must be heavy enough not to float during the operation of the apparatus. In cases of non-automatic 60 operation this limitation does not apply.

65 This invention is illustrated in the accompanying drawings, in which

70 Fig. 1 is a sectional view of the tank, siphon, bell and springs, the lowered position 80 of the bell being shown in dotted lines.

Fig. 2 is a fragmentary view of a non-automatic form of this device.

75 Referring to Fig. 1, A is the flush tank; B is the bell; C is the discharge pipe of the siphon; D is the sewer; F is a fin in the bell B; GG are the walls of the tank; H is the manhole ring; I is the manhole cover; J is the floor of the tank; LL is the automatic flushing level of the liquid; KK is the level of the liquid when the energy storing downward pull on bell B begins; MM is the lowest position of the mouth of the bell B; N is the water supply valve; O is the top level of the liquid seal; P is the maximum vertical height attainable by O; and EE are springs.

90 The operation of the apparatus thus described is as follows: The flush tank becoming filled with water from the supply valve N up to the level indicated by line LL auto- 95

100

matically flushes or discharges its contents because of the head attained, in the usual manner into the sewer D and in progress of this discharging of the tank the liquid level 5 falls therein to the line KK. After this level has been reached all the liquid subsequently discharged must be lifted above the level of the line KK (within the bell) in order to escape through C to D as indicated by the arrows. This puts into action a downward pull 10 on the bell B, which pull increases as the discharge continues to lower the level of the liquid in A outside of B. This downward pull draws the bell downward until the fin F is in contact with the top of C, thus extending the 15 springs EE and storing energy in them. When the level of the liquid in the tank A has fallen to the line MM then the siphon breaks because some air is drawn into the bell B 20 from the tank A. This ends the action of discharging the tank A as the bell B has reached its lowest possible position due to the impinging of F upon the top of C. The downward pull due to the siphonic action 25 within B is now weakened and no longer able to hold down the bell B against the upward pull of the springs EE which have been extended by the downward movement of the bell; hence the springs lift the bell back, up 30 to its original level as shown in full lines in Fig. 1, leaving the liquid level in the tank at MM below the bottom of the bell B, which now loses all its liquid contents by gravity. The air chamber within B and C down to O 35 is now automatically recharged with air from the tank A. As the inflow of liquid from the supply N is continuous the same action as described will repeat itself continually.

If it is desired to operate this invention 40 non-automatically the incoming liquid must not be allowed to reach the level of the line LL, but must be shut off by some usual or suitable means such as a ball float and valve. Such an arrangement is shown in Fig. 2. Referring to said figure, when a flush is desired 45 a lowering of the bell B' by pressure from above or downward pull from below or otherwise will cause the discharge of the flush tank A by increasing the head of the liquid within 50 said flush tank beyond the height of the liquid seal P, as shown in Fig. 1, which height P cannot be increased. In Fig. 2 the regulation of the upper liquid level L'L' is by means of a ball float Q controlling a valve S 55 in the inlet pipe N; and the downward movement of the bell B' to flush is produced by pressure downwardly on a push rod R which is maintained in its upper or normal position by a spring E', which performs all the same 60 functions as the springs E in Fig. 1. Otherwise than in the initial step of pushing down on rod R, the operation is the same and depends on the same principles as before.

Obviously any other suitable mechanical 65 or other means may be substituted for the

mechanism shown, without departing from the scope and purview of this invention. It is to be understood that all non-essential modifications and additions to the specific means herein described and illustrated are contemplated as within the scope of the appended 70 claims. Thus any desired or usual form of overflow may be provided in Fig. 2. Again, the bell B' in Fig. 2 is not necessarily heavy enough to prevent its floating, as it is held 75 against flotation by the pin T.

What is claimed is:

1. In an air bound siphon flushing apparatus, a movable bell forming part of a siphon, and a yieldably resistant means utilizing the 80 downward pull exerted upon the air bell by the discharging liquid during the flushing operation to store up energy, and means timed to release said energy to restore the air bell, after the flushing operation, to its normal 85 position.

2. In an air bound siphon flushing apparatus, a pipe with a depending liquid seal, a movable bell forming a part of the siphon and means utilizing the downward pull exerted upon said bell during the flushing action to draw the bell downward, means actuated thereby to store up energy and means thereafter actuated to release said energy and apply the same to restore the bell to its normal 95 position.

3. In an air bound siphon flush tank, a tank, a pipe extending downwardly out of the tank and turned upwardly to form a liquid seal, said pipe also extending upwardly 100 above the bottom of said tank, a bell positioned over and enclosing the upper part of said pipe within the tank, said bell being held in normal position by yieldably resistant means which will permit of the downward motion of the bell when acted on by siphonic pull and restore the bell to its normal level after the discharge of the tank.

4. In an air bound siphon flush tank, a tank, a pipe extending downwardly out of the tank and turned upwardly to form a liquid seal, said pipe also extending upwardly above the bottom of said tank, a bell positioned over and enclosing the upper part of said pipe within the tank, said bell being held in normal 110 position by yieldably resistant means which will permit of the downward motion of the bell when acted on by siphonic pull and restore the bell to its normal level after the discharge of the tank, and means for non-automatically discharging the tank by downward motion of the bell when the tank contains liquid almost enough to cause flushing 115 automatically.

In testimony whereof I hereunto affix my 120 signature.

HARMON D. MOISE.
